(57) **CLAIM**

The ornamental design for a front receiver for gutter guard assembly as shown and described.

DESCRIPTION

FIG. 1 is a perspective view of a first embodiment of a front receiver for gutter guard assembly;

FIG. 2 is another perspective view of the front receiver for gutter guard assembly of FIG. 1;

FIG. 3 is a top plan view of the front receiver for gutter guard assembly of FIG. 1;

FIG. 4 is a bottom plan view of the front receiver for gutter guard assembly of FIG. 1;

FIG. 5 is a front elevation view of the front receiver for gutter guard assembly of FIG. 1;

FIG. 6 is a rear elevation view of the front receiver for gutter guard assembly of FIG. 1;

FIG. 7 is a right-side elevation view of the front receiver for gutter guard assembly of FIG. 1;

FIG. 8 is a left-side elevation view of the front receiver for gutter guard assembly of FIG. 1;

FIG. 9 is a perspective view of a second embodiment of a front receiver for gutter guard assembly;

FIG. 10 is another perspective view of the front receiver for gutter guard assembly of FIG. 9;

FIG. 11 is a top plan view of the front receiver for gutter guard assembly of FIG. 9;

FIG. 12 is a bottom plan view of the front receiver for gutter guard assembly of FIG. 9;

FIG. 13 is a front elevation view of the front receiver for gutter guard assembly of FIG. 9;

FIG. 14 is a rear elevation view of the front receiver for gutter guard assembly of FIG. 9;

FIG. 15 is a right-side elevation view of the front receiver for gutter guard assembly of FIG. 9; and,

FIG. 16 is a left-side elevation view of the front receiver for gutter guard assembly of FIG. 9.

The broken lines shown in the drawings illustrate portions of the front receiver for gutter guard assembly that form no part of the claim.
